HARMONICA

William De Warel Switzer, Jr., Berkeley, Calif.
(General Delivery, Woodacre, Calif. 94973)

Filed Aug. 24, 1970, Ser. No. 24,658

Term of patent 14 years

Int. Cl. D17—02

U.S. Cl. D56—1

FIG. 1

FIG. 2

FIG. 5

FIG. 3

FIG. 6

FIG. 4

FIG. 1 is a bottom, front and right end perspective view of a harmonica, showing my new design;

FIG. 2 is a front elevational view;

FIG. 3 is a bottom plan view, the top being substantially a mirror image thereof;

FIG. 4 is a rear elevational view;

FIG. 5 is an end elevational view looking at the left end in FIG. 2; and

FIG. 6 is an opposite end elevational view looking at the right end in FIG. 2.

I claim:

The ornamental design for a harmonica, substantially as shown and described.
